UNITED STATES PATENT OFFICE.

FRED J. BULLOCK, OF SHORTSVILLE, NEW YORK, ASSIGNOR TO PAPEC MACHINE COMPANY, OF SHORTSVILLE, NEW YORK, A CORPORATION OF NEW YORK.

ROTARY CUTTING-WHEEL.

1,244,171.

Specification of Letters Patent. Patented Oct. 23, 1917.

Application filed May 2, 1916. Serial No. 94,939.

To all whom it may concern:

Be it known that I, FRED J. BULLOCK, a citizen of the United States, residing at Shortsville, in the county of Ontario and State of New York, have invented certain new and useful Improvements in Rotary Cutting-Wheels, of which the following is a specification, reference being had therein to the accompanying drawing.

10 This invention relates to certain new and useful improvements in rotary cutting wheels used in ensilage cutters, the object being to provide a cutting wheel which is so constructed that the knives carried thereon will be prevented from becoming choked by the material being cut, means being provided in connection with the knife supports for allowing the material to pass under the knives.

20 Another object of my invention is to provide a cutting wheel with an offset portion forming a recess under the knife supports having an inclined bottom which allows the material cut by the knives to pass under the same between the knife supports, thereby overcoming the disadvantages now existing with cutting wheels of this character when cutting certain kinds of material.

30 Another and further object of the invention is to provide a cutting wheel which is provided with stops for the knife supports so as to relieve the bolts from the thrust of the knives.

35 Other and further objects and advantages of the invention will be hereinafter set forth and the novel features thereof defined by the appended claims.

In the drawing—

40 Figure 1, is a plan view of a portion of a wheel constructed in accordance with my invention showing one of the cutting knives mounted upon a pair of supports; and

Fig. 2, is a section taken on the line 2—2 of Fig. 1.

45 Like numerals of reference refer to like parts in the several figures of the drawing.

In carrying out my invention, I employ a circular cutting wheel as shown in my companion case, on which is adapted to be mounted a series of tangentially arranged cutting blades and while in the drawing, I have only shown a portion of the wheel, it is, of course, understood that the wheel will

be constructed at each blade, as shown in the segments illustrated in Figs. 1 and 2, the construction of which will be hereinafter fully described.

Arranged on the face of the cutting wheel 1 at equal distances, is a cutting blade 2 mounted upon supports 3 in substantially the same manner as shown in my companion case, with the exception that the supports are provided with bosses 4 fitting in recesses 5 formed in the face of the wheel surrounding the securing bolt 6, as clearly shown in Fig. 2, which receives the end thrust of the support and in order to provide additional means for this purpose, the face of the wheel is provided with a lug 7 at each support.

70 The supports 3 are secured in position upon the wheel and are adjusted in a similar manner to that disclosed in my companion case, above referred to.

In order to prevent the material being cut by the knives 2 from wedging under the knives and choking the cutting wheel when in operation, I provide the wheel with an offset portion 8 which forms a recess 9 under the spaced supports 3, said recess having a 75 tapering or inclined bottom 10 terminating flush with the face of the wheel at 11 and an inclined wall 12 terminating at the face of the wheel to the rear of the cutting blade.

80 As the material is cut by the knife 2 when the wheel is being rotated, in cutting certain kinds of material, the material wedges under the knife and the face of the wheel so as to choke the cutting wheel and I have found that by providing a cutting 85 wheel with an inclined recess extending from a point approximately in line with the cutting edge of the knife, to the rear of the cutting knife, the cut material will pass between the knife and wheel without 90 wedging, thereby preventing the cutting wheel from being choked.

95 While I have shown a recess constructed in a particular manner in order to prevent the knives of the wheel from becoming 100 choked by the material being cut, I do not wish to limit myself to the exact construction of recess shown, as the object of my invention is to provide means for preventing the material from accumulating under 105 the knife by providing the wheel with a

recess which can be formed of various shapes without departing from the spirit of my invention.

In cutter wheels of this character used in connection with ensilage cutters, the knives are set at an angle in respect to the face of the cutting wheel so that the material is wedged under the knife and the face of the wheel as the cutting edge of the knife is at a greater distance from the face of the wheel than the rear edge of the knife and I have found that by providing the face of the wheel with a recess having an inclined bottom under the knife extending from the cutting edge to the rear of the knife, that the distance between the knife and the bottom of the recess is gradually increased as the material is forced under the same so as to prevent the wedging action, whereby a self-clearance is obtained.

It will be seen that I have provided a cutting wheel for an ensilage cutter with the recess arranged between the supports and to each side thereof in order to provide an ensilage cutter with a self clearing knife so as to prevent the material being cut from wedging under the knife, and while in the drawing I have shown this recess formed of such a size that it extends out to each side of the knife, I do not wish to limit myself to the size of recess employed as in some cases it might be found that a recess located solely between the supports will accomplish the desired result.

From the foregoing description, it will be seen that I have provided a cutting wheel for an ensilage cutter of a series of tangentially arranged cutting knives mounted upon spaced supports over recesses formed in the cutting wheel in order to allow the material being cut by the knives to pass under the knives.

I claim:

45 1. A rotary cutting wheel for ensilage cutters having a disk-shaped wheel body, a series of cutting knives mounted on one face thereof, said wheel body being provided with a clearing recess under each cutting knife having an inclined face diverging from a point in transverse alinement with the cutting edge of said knife.

50 2. A rotary cutting wheel for ensilage cutters having a disk-shaped wheel body, a series of cutting knives mounted on one face thereof, and spaced therefrom, said wheel body having a clearing recess with an inclined bottom under each of said cutting knives presenting an inclined face in respect to the face of the knife.

55 3. A rotary cutting wheel for ensilage cutters having a disk-shaped wheel body, spaced knife supports mounted on one face thereof provided with inclined knife seats, 60 knives mounted in said seats, said wheel

body having a recess formed in one face thereof under each pair of supports presenting an inclined face diverging from a point in transverse alinement with the cutting edge of the knife, and terminating at a point to the rear of the knife.

4. A rotary cutting wheel for ensilage cutters, comprising a cutting wheel having a series of recesses formed in one face thereof, a pair of knife supports mounted on the face of said wheel over each of said recesses, and a knife secured upon said supports, each of said recesses having an inclined face at an angle to the face of said knife.

5. A rotary cutting wheel for ensilage cutters, comprising a disk-shaped wheel body having a series of clearing recesses formed in one face thereof provided with inclined bottoms, an adjustable knife support mounted over each of said recesses, and a knife mounted upon said support.

6. A rotary cutting wheel for ensilage cutters, comprising a disk-shaped wheel body having a series of offsets formed on one face thereof producing a series of recesses upon the opposite face, a knife support mounted over each of said recesses, a knife mounted on said supports, said recesses having inclined bottoms presenting an inclined face in respect to the face of the knife.

7. A rotary cutting wheel for ensilage cutters having a disk-shaped wheel body, said wheel body having a series of recesses formed in one face thereof, cutter knives mounted on said wheel body over said recesses, said recesses extending from a point in transverse alinement with the cutting edge of said knife and terminating at a point to the rear of the knife.

8. The combination with a rotary cutting wheel having a series of recesses formed in one face thereof provided with inclined bottoms, of supports arranged over each of said recesses, means for adjusting each of said supports, and a cutting knife mounted upon each pair of supports having a cutting edge in alinement with one end of said recess.

9. A rotary cutting wheel having a pair of supports mounted upon one face thereof, a cutting blade carried by said supports and arranged at an angle to the face of said wheel, said cutting wheel having a recess formed therein under said supports extending from a point in alinement with the cutting edge of said knife to the rear of said knife.

10. A cutting wheel for ensilage cutters, comprising a disk-shaped wheel body having a clearing recess formed in one face thereof provided with an inclined bottom, knife supports adjustably mounted over said recesses, said wheel body having recesses formed therein, a knife mounted on said supports over said recesses, said supports

having bosses fitting in the recesses formed in the wheel body, and bolts passing through said bosses and wheel body for securing said supports in position over said clearing recesses.

5 11. In an ensilage cutter, the combination with the cutting wheel having recesses formed in one face thereof, knife supports having bosses at one end thereof mounted 10 within said recesses, said wheel having lugs extending outwardly from the face thereof to the rear of said supports and engaged thereby, and bolts passing through said supports and wheel.

15 12. A cutting wheel for ensilage cutters having a series of clearing recesses formed in one face thereof and a cutting knife mounted over each of said recesses.

20 13. An ensilage cutter having a rotary knife carrying wheel provided with a disk-shaped wheel body, a series of spaced pairs of knife supports mounted on one face of

said wheel body, bolts for securing said supports upon said wheel body, said wheel body being provided with clearing recesses, knives 25 carried by said supports, said wheel body having recesses spaced from said clearing recesses, and bosses formed on said supports extending into the last-mentioned recesses.

14. A cutting wheel for ensilage cutters 30 having a series of recesses formed in one face thereof, a knife mounted over each of said recesses, each of said recesses having an inclined face diverging from a point in transverse alinement with the edge of the 35 knife and terminating at a point to the rear of the knife.

In testimony whereof I hereunto affix my signature in the presence of two witnesses.

FRED J. BULLOCK.
